United States Patent

Des. 236,981
Patented Sept. 30, 1975

236,981

DOOR FOR VACUUM FURNACE

Donald L. Winslow, Lake Arrowhead, Calif., assignor to
The J. M. Ney Company, Bloomfield, Conn.

Filed Jan. 21, 1974, Ser. No. 434,659

Term of patent 14 years

Int. Cl. D24—01, 99; D23—03

U.S. Cl. D23—82

FIG. 1

FIG. 2

FIG. 3

FIG. 4

FIG. 5

FIG. 6

FIG. 1 is a front elevational view of a door for vacuum furnace showing my new design;

FIG. 2 is a bottom plan view thereof;

FIG. 3 is a rear elevational view thereof;

FIG. 4 is a top plan view thereof;

FIG. 5 is an elevational view of the left side thereof as seen in FIG. 1; and

FIG. 6 is an elevational view of the side opposite to that in FIG. 5.

I claim:

The ornamental design for a door for vacuum furnace, as shown.
